OXYGEN REGULATOR

Carl H. Sollmann, Montclair, N. J., assignor to
Kidde Manufacturing Co., Inc., Bloomfield,
N. J., a corporation of Delaware

Application June 7, 1946, Serial No. 675,284

13 Claims. (Cl. 128—142)

1

This invention relates to improvements in oxygen regulators and particularly to devices for regulating the flow of oxygen and/or the oxygen and air ratio in breathing devices.

The device of the present invention is particularly well adapted for use in aircraft at high altitudes for supplying the proper amount of oxygen and/or oxygen and air mixtures for breathing purposes.

Devices of this character as heretofore known have been of such size and weight as to be unsuited for insertion or adaptation to breathing masks.

Accordingly, one of the objects of the present invention is the provision of a device of the character indicated which has many advantages over, and overcomes inherent disadvantages in, such device as heretofore known.

Another object of the invention resides in the provision of a device which is compact, light in weight, and of rigid construction, desiderata in devices of this character.

A further object of the invention is the provision of a device of the character indicated which can be mounted on and carried by a mask.

A further object of the invention resides in the provision of a device of the character indicated which is entirely automatic and which regulates the oxygen and/or the oxygen-air ratio to provide for proper breathing at various altitudes.

A further object of the invention resides in the provision of a device which, at all times, is under the automatic control of the operator's respiratory system.

A still further object of the invention resides in the provision of a device of the character indicated wherein the automatic regulation is accomplished through the medium of a novel valve mechanism and valve control means actuated by the human respiratory system.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

2

Figure 1 is a sectional elevational view of a device in accordance with the invention.

Figure 2 is a sectional view taken on line 2—2 of Figure 1.

Figure 3 is a top view thereof.

Figure 4 is a side elevational view of the device.

Figure 5 is a fragmentary sectional view on line 5—5 of Figure 1.

Figure 6 is a side elevational view partly in section.

Figure 7 is a fragmentary sectional view taken on line 7—7 of Figure 6; and

Figure 8 is a sectional view of a modified form of the device showing the same applied to a mask.

Referring to the drawings in detail, the unit shown may be adapted for use with breathing equipment of any kind, such as that wherein the unit may be supported separately from the user, or on his chest, or otherwise, the embodiment chosen for illustration is one in which the entire equipment except an oxygen source is adapted to constitute part of a small, light-weight mask unit which may be handled more readily than where the equipment is mounted on the user's chest or otherwise.

The feature wherein the unit may be mounted on and carried by a mask, without appreciably increasing its size or weight, is a result of novel construction which will be apparent from the following explanation of the principles, construction and operation involved.

Referring to the drawings in detail and more particularly to Figures 1 to 7 thereof, there is shown an oxygen regulator in accordance with the invention having a terminal or coupling element 16 constituting an oxygen inlet to which oxygen is adapted to be supplied from a suitable source by means of a valve controlled conduit (not shown).

From the inlet 16, the oxygen is conducted through a conduit 18 to a main or demand valve chamber housing 20, a main or demand valve 21 and an outlet 22. The main valve 21 includes a valve member 24 for engagement with a main valve seat 26, which valve member is urged away from its seat by a spring 28. The outlet 22 leads, through a conduit 30 (Figure 2), to inlet 31 of a chamber 32 formed in a housing 40 mounted on the casing of the device. The casing of a diluter 33 extends about the housing 40 is adapted to be moved relatively thereto by an aneroid bellows 41. This casing is formed with a jet 36 and the fixed housing 40 carries a needle valve

55

member 109 so that, when the diluter casing is moved by the bellows, the jet 36 moves relative to the valve member 109 whereby the latter will control the flow of oxygen through the jet 36 to a mixing chamber 34. The housing 40 and the jet 36 are disposed in alignment with a respirator 42 having a check valve 44 therein. The diluter 33 and mixing chamber 34 are employed when the device is utilized to supply a mixture of air and oxygen as will be described in more detail hereinafter.

The main valve member 24 is provided with a hollow valve stem or sleeve 46 which constitutes a single conduit providing communication between the main valve chamber housing 20 and the pressure side 48 of a main valve operating diaphragm 50 to which the stem 46 is connected, in diaphragm chamber 52, by means of nuts 51 and 53 (Figure 1).

As shown in Figure 2, a conduit 56 provides communication between the pressure side 48 of the diaphragm 50 and a pilot valve structure 54 having a valve seat 57 for a pilot valve member 58 which is connected to a pilot diaphragm 60 in a pilot diaphragm chamber 62. An adjustable spring mechanism 64 urges the pilot diaphragm 60 toward the open position of the pilot valve member 58 relative to the seat 57. An exhaust conduit 66 of the respirator 42 communicates with pressure side 70 of the pilot diaphragm 60 in the chamber 62, whereby exhalation pressure is built up on the pressure side 70 of the pilot diaphragm to close the pilot valve 58, and on inhalation the said pressure is released whereby to permit the pilot valve to open under the action of the spring mechanism 64.

The respirator 42 is provided with a mouth piece 72 (Figure 1), which may be received by the lips of the user when no mask is employed, and which fits into an intake or mouth piece receptacle 74 of a mask 76 when the device is employed with a mask as shown in fragmentary view in Figure 1. The respirator has an inlet facing the jet 36 and has an outlet extending into the mask 76, and the valve 44 is positioned between the inlet and outlet.

In operation, with the mask on the face of the operator and the respirator 42 opposite his mouth and nose, he opens the discharge valve 12 of the oxygen supply source 10 to release oxygen directly to the inlet 16. The check valve 44 and the pilot valve diaphragm 60 are so delicately responsive to breath pressure that the first effect after opening the discharge valve 12 will depend upon whether the user, or aviator, is inhaling or exhaling at the moment.

If he is exhaling, the check valve 44 will close, whereby, the exhalation pressure will be bypassed through conduit 66 to the pilot diaphragm 60 and will close the pilot valve 58, whereupon the oxygen pressure through the main valve member 24 and its stem 46, and through the conduit 56 to the pilot valve 54, will build up and operate as a back pressure against the main valve diaphragm 50 which will move the main valve member 24 against the action of the spring 28 to seat against the seat 26 and close communication between the conduit 18 and outlet 22, thereby stopping the flow of oxygen to the respirator 42.

Upon inhalation, the reverse action takes place, resulting in the release of exhalation pressure, on the check valve 44 permitting the same to open, and the release of pressure on the pilot diaphragm 60 permitting the spring mechanism 64

to open the pilot valve 54. This action relieves the pressure on the main valve diaphragm 50, whereupon the main valve member 24 moves from its seat 26 under the action of spring 28 and establishes communication through the main valve chamber 20 from the conduit 18 to the outlet 22, and from the latter through the conduit 30, the chamber 32 and the chamber 34 to the respirator 42.

In breathing equipment as heretofore employed, it was necessary for the user to breathe directly against a diaphragm and the main flow oxygen pressure, there being no mechanism provided corresponding to the pilot valve 54. Therefore, to operate such prior devices, it was necessary to provide a diaphragm of very great area.

In applicant's device, the actual force at the pilot valve is so small that the area of the diaphragm is but a very small fraction of the area of the diaphragm formerly employed. Moreover, since the oxygen pressure itself is many times that of exhalation, the main valve diaphragm of the device of the present invention is also very greatly reduced in area.

The unit of the present invention, although it employs two diaphragms, is so compact and the bulk and weight of the regulator as a whole is so reduced over prior devices that it is readily adaptable as a component part of a mask unit, which has not heretofore been possible.

The breathing equipment of the present invention is suitable for use at high altitudes, or under other circumstances where a supply of pure oxygen may be desired instead of a mixture of air and oxygen.

In such case, the device of the present invention is provided with means whereby the air supply can be shut off, or as shown in Figure 8, the aneroid bellows, and diluter features are eliminated as will be described hereinafter.

When the device thus far described is to be employed for supplying pure oxygen, such as is required at very high altitudes, the diluter is rendered ineffective so that there is no mixing of the oxygen with air. This is accomplished by manually moving the jet 36 to the left, as viewed in Figure 1, by means of a knob 80 secured by a screw 82 to a slide 84. The slide 84 has an inwardly extending projection 86 in alignment with an annular shoulder 88 on the jet 36, whereby upon engagement of the projection 86 therewith the jet is moved to close off air inlet 90. With the air supply closed off as just described pure oxygen is fed directly to the respirator 42. The jet is adapted to be latched in closed position by means of a leaf spring 92 secured at one end to a main housing 94 having a detent 96 at its free end. This detent is adapted to be latched in notches 98 and 100 formed in the inner face of the slide 84. In the position illustrated the slide is latched in position to permit the jet to open. Should the slide be moved to the left to close the jet, the detent 96 of the spring 92 will engage the notch 98 whereby to latch the jet in closed position.

The housing 94, preferably is of light weight material such as aluminum, magnesium, plastic or the like, and is provided with a removable cover 102 which supports a screen 104 whereby air is admitted to the housing. This housing 20 is provided with the oxygen inlet coupling 16 and which as previously mentioned communicates with the oxygen supply source.

When it is desired that the supply to the operator be a mixture of oxygen and air, the diluter 33 shown in Figure 1 is brought into op-

eration. This diluter comprises the aneroid bellows 41 secured to the housing 94 by a nut 106 which is screwed on a threaded projection 107 of the bellows. The bellows is adapted to expand and contract in accordance with different atmospheric pressures at different altitudes. The bellows 41 is provided with a recess 108 for the reception of the diluter casing (Figure 1), and this casing is actuated by the bellows 41 automatically in accordance with altitude. The needle valve 109 has a valve stem 110 provided with a threaded end for securing the same in the housing 40. The housing 40 is secured to the casing or housing 94 by means of screws 112 (Figure 2). The diluter casing, in which the jet 36 is formed, is normally urged by a spring 114 to the right, as viewed in Figure 1. The needle valve 109 is tapered, whereby to provide a metering valve for oxygen passing from the chamber 32 to the mixing chamber 34 through the jet 36.

When the bellows 41 expands, the end of the diluter casing in which the jet 36 is formed will be moved toward the mixing chamber 34, relatively to the housing 40, whereby to reduce the amount of air passing through the air inlet 90, and when the bellows expands sufficiently the wall of the diluter casing surrounding the jet 36 will engage a seat 118 and close off the air supply completely so that only oxygen will pass to the respirator 42, in the same manner as when the air inlet is closed manually as previously described.

On inhaling through the respirator 42, the check valve 44 is opened to the mixing chamber 34. When the air inlet 90 is open, air is free to pass into the mixing chamber from the interior of the housing 94, and oxygen will be fed to the mixing chamber from the source of supply, in the manner hereinbefore described, whereby the air and oxygen will be mixed in the chamber 34. When the air inlet 90 is closed pure oxygen from the chamber 34 will pass the valve 109, as previously mentioned.

The tension on the diaphragm 60 is adjustable by means of the spring mechanism 64 whereby the pressure required to close valve 58 is determined. This mechanism includes a leaf spring 65 which is under an upward force exerted by torsion spring 68 (Figure 6) which torsion spring is fastened to and adapted to be manually adjusted by the rotation of rod 73.

One end of the rod 73 is pinned to locking sector 68 (Figure 7) having notches 83 in its periphery. The other end of the rod 73 is pinned to knob 79. Detent spring 81 is arranged to hold sector 78 in either of two predetermined positions. It is to be understood that additional notches may be provided in the sector whereby the same may be held in additional positions. Rotation of rod 73 winds or unwinds the torsion spring depending on the direction the knob 79 is turned.

When the diaphragm 60 is operated to open the main valve 21, the oxygen passing through the valve stem 46 of the valve 24 and through the conduit 56 escapes to the interior of the housing and commingles with the air therein so that regardless of the amount of oxygen supplied by the diluting mechanism there will also be a certain quantity of oxygen in the air drawn into the mouthpiece.

The unit shown in Figure 8 is designed for use at high altitudes where pure oxygen is desired and accordingly this unit is not provided

with a diluter or aneroid bellows. In many other respects, however, the unit of this figure is substantially the same as that of Figures 1 to 7 inclusive, in that it is provided with the novel main demand and a pilot valve. The main valve in this figure is designated 150 and has a valve member 152 adapted to be seated against a valve seat 154. This valve is similar in construction to the valve 21 of Figure 1 in that it has a hollow stem 156 secured to a diaphragm 158 and provided with a spring 160 for urging the valve toward its seat 154. The hollow stem communicates with the pressure side of the diaphragm 158.

This unit also has a pilot diaphragm 162 which carries a valve member 164. This valve member serves the same function as the valve member 109 of Figure 1, but instead of it being of the needle valve type it engages a ball valve 166, which is adapted to seat on valve seat 168 to close off the escape of pressure from the pressure side of the diaphragm 158 whereby pressure is built up therein to seat the valve 152 and close off the supply of oxygen upon exhalation, as in the previously described embodiment of the invention. A conduit or communicating passageway 170 comparable to the conduit 66 of Figure 1 is provided in the housing 171 leading from a respirator 172 to the pressure side 174 of the pilot diaphragm 162, whereby to actuate the diaphragm as aforesaid.

The pilot valve stem 164 is adapted to be locked in valve closed position by means of a locking pin 176 adapted to be engaged by an arm 178 pivoted to the housing 171 at 180. This arm is adapted to be actuated by a valve locking cam 182 which is keyed to a shaft 184.

A lock wheel 186 is also mounted on the shaft 184, and is provided with peripheral depressions 188, which in this case are six in number, and are adapted to be engaged by a ball 190 which is held in engagement with one of the depressions 188 by means of a spring (not shown).

A check valve is provided for the respirator 172 for venting exhalation pressure in excess of that passing through conduit 170 to the pressure side of the pilot diaphragm. The excess exhalation pressure is vented to atmosphere by way of passageway 175. The check valve comprises a valve disk 192 and a valve stem 194 adapted to slide in a sleeve 196 mounted in the respirator. A lever 198 pivotally mounted at 200 to the housing 171 has a projecting arm 202 carrying a pin 204 which is engaged by a spring 218 whereby to maintain the lever in engagement with the check valve disc 192. Two torsion springs 218 and 220 are keyed to a shaft 184 which shaft is adapted to be manually operated and set in various positions upon rotation of an adjusting knob (not shown), secured to the shaft at the outside of the housing. Upon rotation of this knob in a direction to wind up the torsion springs 218 and 220, the spring 218

will increase the force on the check valve 192 through the medium of arm 202 and lever 198, and spring 220 will increase the force on the diaphragm 162 through the medium of the arm 178. The increase in the force acting on the check valve 192 and on the diaphragm 162 results in maintaining a higher pressure in the mask. Rotation of the adjusting knob in the opposite direction reverses the action and results in maintaining a lower pressure in the mask. This adjustment corresponds to the adjustment accomplished by the adjustable spring

mechanism 64 of Figure 2, since it is an adjustment for diaphragm loading. In the embodiment shown in Figure 8, however, the feature of check valve loading is added.

The respirator 172 includes a mouthpiece 208 which is received by a mouthpiece receptacle 210 of a mask 212.

The operation of the unit of Figure 8 is quite similar to that of the other embodiment previously described, in that upon exhaling the exhalation pressure through passageway 170 will operate the pilot diaphragm 162 whereby to seat the ball valve 166 closing off the escape of pressure from the pressure side of the diaphragm 158 and building up pressure on the pressure side of that diaphragm.

The building up of this pressure will flex the diaphragm 158 whereupon the demand valve 150 will be closed to close off the supply of oxygen to the mask through conduit 216. Upon inhaling the pressure on the pilot valve diaphragm 162 is released, permitting the valve 166 to open, relieving pressure on the pressure side of the demand valve diaphragm 158 and permitting the demand valve to open whereby oxygen will be drawn through the conduit 216 into the nostrils of the user.

As will be seen from Figure 8, the unit illustrated is somewhat smaller than the unit of Figure 1, by reason of the omission of the diluter features. The unit of Figure 8 readily fits into a mask and adds very little weight to the mask, whereby the mask with the unit can be worn comfortably.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

I claim:

1. In breathing equipment, a respirator, means for conducting a flow of oxygen under pressure to said respirator including main valve means movable to open and close said flow conducting means, pressure responsive means for controlling said main valve means including a conduit for conducting pressure medium thereto, pilot valve means for controlling the effectiveness of the pressure medium on said pressure responsive means, means responsive to respiration for controlling the operation of said pilot valve means including conduit means connecting said respirator to said respiration responsive means, and check valve means in said respirator responsive to exhalation to direct exhalation through said conduit means.

2. In breathing equipment, a respirator, means for conducting a flow of oxygen under pressure to said respirator including main valve means movable to open and close said flow conducting means, pressure responsive means for controlling said main valve means including a conduit for conducting pressure medium thereto, pilot valve means for controlling the effectiveness of the pressure medium on said pressure responsive means, means responsive to respiration for controlling the operation of said pilot valve means, and means for adjusting said respiration responsive means for response to a predetermined pressure.

3. In breathing equipment, a respirator, means for conducting a flow of oxygen under pressure to said respirator including main valve means

movable to open and close said flow conducting means, pressure responsive means for controlling said main valve means including a conduit for conducting pressure medium thereto, pilot valve means for controlling the effectiveness of the pressure medium on said pressure responsive means, means responsive to respiration for controlling the operation of said pilot valve means, means including a rotatable rod and spring means mounted thereon opposing the pressure due to exhalation in said respiration responsive means, and manually operable means for rotating said rod to effect adjustment of said spring means.

4. In breathing equipment, means for supplying oxygen under pressure, a respirator, means for conducting a flow of oxygen under pressure from said supply means to said respirator including main valve means movable to open and close said flow conducting means, pressure responsive means for controlling said main valve means including a passage for conducting oxygen from said supply means to said pressure responsive means and including a vented passage, pilot valve means for controlling said vented passage to control the effectiveness of the oxygen on said pressure responsive means, and means responsive to respiration for controlling the operation of said pilot valve means including conduit means connecting said respirator to said respiration responsive means.

5. In breathing equipment, means for supplying oxygen under pressure, a respirator, means for conducting a flow of oxygen under pressure from said supply means to said respirator, main valve means including a member movable to open and close said flow conducting means, diaphragm means for controlling movement of said main valve member including a vented passage and including a passage extending through said main valve member for delivering oxygen under pressure from said flow conducting means to said diaphragm means, pilot valve means for said vented passage for controlling the effectiveness of the pressure of the oxygen on said diaphragm means, and means responsive to respiration for controlling the operation of said pilot valve means including conduit means connecting said respirator to said respiration responsive means.

6. In breathing equipment, a respirator having an inlet and an outlet, means for conducting a flow of oxygen under pressure from a source of supply to said respirator inlet, said means including a main valve chamber having an oxygen entrance and an exit to said respirator inlet, a main diaphragm chamber, a main diaphragm in said main diaphragm chamber, a main valve member in said main valve chamber including a hollow stem connected to one side of said main diaphragm and constituting conduit means communicating between said oxygen entrance and said main diaphragm chamber at the other side of said main diaphragm, spring means for normally positioning said main valve member to establish communication through said main valve chamber between said entrance and said exit, a pilot valve having an opening communicating with said other side of the main diaphragm, a pilot diaphragm chamber, a pilot diaphragm responsive to exhalation pressure in said pilot diaphragm chamber, a pilot valve member connected to one side of said pilot diaphragm for controlling said opening, means including pilot spring means urging said pilot valve member to unclose said opening, means for adjusting said pilot valve spring means, a check valve in said

respirator between said inlet and outlet thereof responsive to exhalation pressure for restricting flow from said respirator inlet to said respirator outlet, and conduit means connecting said respirator outlet to said pilot diaphragm chamber.

7. In breathing equipment, a respirator having an inlet and an outlet, a casing in communication with said respirator inlet, means in said casing for conducting a flow of oxygen under pressure from a source of supply to said respirator inlet, said means including a main valve chamber having an oxygen entrance and an exit to said respirator inlet, a diaphragm chamber in said casing, a main diaphragm in said main diaphragm chamber, a main valve member in said main valve chamber including a hollow stem connected to one side of said diaphragm and constituting conduit means communicating between said oxygen entrance and the other side of said diaphragm, spring means for normally positioning said main valve to establish communication between said main valve chamber entrance and exit, a pilot valve in said casing having an opening communicating with said other side of said diaphragm, a pilot diaphragm chamber in said casing, a pilot diaphragm responsive to exhalation pressure in said pilot diaphragm chamber, a pilot valve member connected to one side of said pilot diaphragm for controlling said opening, means including pilot spring means urging said pilot valve member toward open position, means for adjusting said pilot spring means, a check valve in said respirator between said inlet and outlet thereof responsive to exhalation pressure for restricting flow from said respirator inlet to said respirator outlet, and conduit means connecting said respirator outlet to said pilot diaphragm chamber.

8. In a device for delivering oxygen to breathing equipment, an oxygen flow regulator comprising a pressure chamber, a diaphragm in one wall thereof, said chamber being adapted for connection in communication with the exhaust of the breathing equipment, a valve carried by said diaphragm, a second pressure chamber and a diaphragm in one wall thereof, an outlet port for said last mentioned chamber controlled by said valve, said first mentioned diaphragm being adapted for actuation by exhalation from the breathing equipment to cause said valve to close said outlet port, an oxygen supply line and a valve member carried by said second diaphragm having a passage extending therethrough, said valve member controlling said oxygen supply line, said passage in said valve member communicating with said second pressure chamber whereby pressure is built up in said chamber when the first mentioned valve is moved to close said outlet port.

9. In a device of the class described, means for delivering a mixture of oxygen and air to a breathing mask, a control pressure chamber, a control diaphragm in one wall thereof, said chamber being in communication with said delivery means, a control valve carried by said control diaphragm; a second pressure chamber and a diaphragm in one wall thereof, an outlet port for said last mentioned chamber controlled by said control valve, said control diaphragm being actuated by exhalation from said mask to cause said control valve to close said outlet port, an oxygen supply line, a valve carried by said second diaphragm for controlling said oxygen supply line, a hollow stem on said last named valve providing communication between said supply line and said second pressure chamber whereby pressure is

built up in said second pressure chamber when said control valve is moved to close said outlet port, means for opening said control valve upon cessation of exhalation from said mask whereby to relieve the pressure in the second pressure chamber and to permit the opening of said valve carried by said second diaphragm to provide a flow of oxygen to said mask, and air inlet means for said mask.

10. In a device for delivering oxygen to breathing equipment, an oxygen flow regulator comprising a pressure chamber having means adapted for communication with the exhaust of the breathing equipment, a valve controlled by pressure in said chamber, a second pressure chamber and a diaphragm in one wall thereof, an outlet port for said last mentioned chamber controlled by said valve, an oxygen supply line, and a valve carried by said diaphragm for controlling said oxygen supply line, said last mentioned valve having a passage extending therethrough and communicating with said second pressure chamber, whereby pressure is built up in that chamber when said first mentioned valve is moved to close said outlet port and the building up of pressure in said second chamber actuates said diaphragm to close said last mentioned valve.

11. In a device for delivering oxygen to breathing equipment, an oxygen flow regulator comprising a pilot pressure chamber having means adapted for connection in communication with the exhaust of the breathing equipment, a pilot valve actuated by pressure in said chamber from the exhaust of the breathing equipment, a second pressure chamber and a diaphragm in one wall thereof, an outlet port for said last mentioned chamber controlled by said valve, an oxygen supply line, a valve member carried by said diaphragm for controlling said oxygen supply line, said valve member having a passage extending therethrough and communicating with said second pressure chamber, whereby pressure is built up in said second chamber when said first mentioned valve is moved to close said outlet port and the building up of pressure in said second chamber actuates said diaphragm to cause said valve member to close said supply line, and means biasing said pilot valve to open position upon release of pressure in said pilot pressure chamber.

12. In a device for delivering oxygen to breathing equipment, an oxygen flow regulator comprising a pressure chamber having means adapted for connection in communication with the exhaust of the breathing equipment, a valve controlled by pressure in said chamber, a second pressure chamber and a diaphragm in one wall thereof, an outlet port for said last mentioned chamber controlled by said valve, an oxygen supply line, a control valve carried by said diaphragm for controlling said oxygen supply line, and conduit means including a passage for by-passing the oxygen pressure around said control valve to the second chamber, whereby pressure is built up in the second chamber when the first mentioned valve is moved to close said outlet port and the building up of pressure in said second chamber actuates the diaphragm to close the control valve.

13. In a device for delivering oxygen to breathing equipment, an oxygen flow regulator comprising a pilot pressure chamber having means adapted for connection in communication with the exhaust of the breathing equipment, a pilot valve actuated by pressure in said chamber from the exhaust of the breathing equipment, a second

11

pressure chamber and a diaphragm in one wall thereof, an outlet port for said last mentioned chamber controlled by said valve, an oxygen supply line, a main valve carried by said diaphragm for controlling said oxygen supply line, conduit means including a passage for by-passing oxygen pressure around said main valve to said second chamber, whereby pressure is built up in said second chamber when said pilot valve is moved to close said outlet port and the building up of pressure in said second chamber actuates the diaphragm to close said main valve, and means biasing said pilot valve to open position upon the release of pressure in said pilot pressure chamber.
